CLAIM

The ornamental design for a hair curler steamer enclosure, as shown and described.

DESCRIPTION

FIG. 1 is a front elevation of the hair curler steamer enclosure design according to our invention;

FIG. 2 is a side elevation of the right side of the hair curler steamer enclosure design shown in FIG. 1;

FIG. 3 is a rear elevation of the hair curler steamer enclosure design shown in FIG. 1;

FIG. 4 is a side elevation of the left side of the hair curler steamer enclosure design shown in FIG. 1;

FIG. 5 is a top plan view of the hair curler steamer enclosure design shown in FIG. 1; and,

FIG. 6 is a view of the bottom of the hair curler steamer enclosure design shown in FIG. 1, the stippling thereon representing a rough textured surface.

The ends of the cord are shown partially broken away in the various views to indicate indeterminate length.
